(57) **CLAIM**

The ornamental design for a cutlery handle, as shown and described.

DESCRIPTION

FIG. 1 is a perspective rear, right side and top view of a cutlery handle showing our new design;

FIG. 2 is a perspective front, left side and top view thereof;

FIG. 3 is a bottom plan view thereof;

FIG. 4 is a top plan view thereof;

FIG. 5 is left-side elevation view thereof;

FIG. 6 is right-side elevation view thereof;

FIG. 7 is a rear elevation view thereof; and,

FIG. 8 is a front elevation view thereof.

The broken lines in the drawings are for illustrative purposes only and form no part of the claimed design.
